SHUTTLE CHECKING DEVICE FOR LOOMS

Sherwood O. Dodge, Medford, Mass., assignor to
Guaranteed Parts, Inc., Allston, Mass., a cor-
poration of Massachusetts

Application October 19, 1940, Serial No. 361,989

4 Claims. (Cl. 139—165)

This invention relates to improvements in shuttle checking devices for looms and particularly to a tension device for a check strap for a picker stick and shuttle.

In the operation of certain looms it has been the custom for many years to utilize a check strap as a means for checking the movement of the picker stick and shuttle and bringing the latter to a stop in the shuttle box. Associated with this check strap is a rigid tension device which frictionally engages the strap with equal pressure during both the incoming and discharge movements of the shuttle in the shuttle box in a manner to cause considerable wear to the strap and thereby making it necessary to replace said strap frequently.

The primary object of this invention is to provide a simple effective device for applying friction to a check strap as the shuttle enters the shuttle box, and for automatically releasing or reducing said friction when the shuttle is discharged from the shuttle box.

Another object of the invention is to provide a device having a pivoted friction member embodied therein which may be reversed to present a new friction surface for engagement with the check strap in the event that the original surface becomes worn excessively.

Still another object of the invention is to provide a structure which will eliminate excessive heating caused by the constant frictional engagements of the friction member with the check strap.

The invention consists of a shuttle checking device for looms as set forth in the following specification and particularly as pointed out in the claims.

Referring to the drawings:

Fig. 1 is a side elevation of an end portion of a lay and associated parts including a shuttle checking device embodying my invention.

Fig. 2 is a horizontal sectional view as taken on the line 2—2 of Fig. 1, illustrating the mechanism of this invention positioned to check the movement of a check strap, and the latter being positioned at the end of the checking movement of the picker stick and shuttle as the latter is brought to a stop in the shuttle box, portions of the lay structure being illustrated in light dash lines.

Fig. 3 is a horizontal sectional view similar to Fig. 2 illustrating the checking device positioned to reduce the friction upon the check strap during the movement of the picker stick to discharge the shuttle from the shuttle box.

Fig. 4 is a sectional plan view illustrating a modified embodiment of the invention.

Fig. 5 is a sectional side elevation of the mechanism illustrated in Fig. 4.

Fig. 6 is a sectional plan view illustrating still another modified embodiment of the invention.

Fig. 7 is a sectional side elevation of the mechanism illustrated in Fig. 6.

Like numerals refer to like parts throughout the several views of the drawings.

In the drawings, referring particularly to Figs. 1, 2 and 3, 10 represents an end portion of the lay of a loom, and 11 represents an end portion of a guide member for a picker stick 12 for said loom, said guide member 11 being attached to the lay at 13 and by other suitable means well known in the art. A check strap 14 for the picker stick 12 is formed as a loop and attached to a holder 15 supported by the lay 10 by means of a clamping structure 16 consisting of a bolt and co-operating washers. Formed integral with the guide member 11 and projecting downwardly therefrom are a pair of friction fingers 17 for the check strap 14, an inner face 18 of which is arranged to slide in opposite directions across a curved surface 19 of each of said fingers as movement is imparted to the check strap by means of the picker stick. The portion of the check strap 14 which is located opposite the clamping means 16 therefor is supported upon forwardly projecting shelves 20 provided at the lower extremities of the friction fingers 17. Also formed integral with the guide member 11 and projecting outwardly and downwardly therefrom is an arm 21, a face of which is grooved at 22 to constitute a guide for a bracket 23 which is movable toward and away from the check strap 14 and which is secured to the arm 21 by a bolt 24. Pivotedly attached to the bracket 23 by means of a pivotal pin 25 is a friction member 26 constructed of a wear and heat resisting material, as, for example, graphited Bakelite, an arcuate surface 27 of which engages the check strap 14 at a point substantially midway between the friction fingers 17 during the movement of the check strap 14 in the direction of the arrow a, Fig. 2, in which direction the check strap is moved by the movement of the picker stick when the latter is contacted by the shuttle 28 as said shuttle enters the shuttle box. The friction member 26 is reversible upon the bracket 23, being provided with two holes 29 for the reception of the pivotal pin 25, and with two arcuate surfaces 27 arranged to contact with the check strap 14, and when one of said arcuate surfaces becomes worn to

such an extent that its effectiveness is impaired the friction member may be repositioned in the bracket 23 to provide a new friction surface for engagement with the check strap. The pivotal movement of the friction member 26 in opposite directions upon the bracket 23 is restricted by stop portions 30 and 31 provided upon said bracket, and in Fig. 2 the friction member is illustrated in contact with the stop portion 30 to which position it is moved by the frictional engagement of the check strap 14 therewith when said strap is moved in the direction of the arrow *a*, Fig. 2, by the picker stick 13 when the latter is contacted by the shuttle 28 as said shuttle enters the shuttle box and is brought to a stop therein.

In Fig. 3 the friction member 26 is illustrated in contact with the stop 31 to which position it is moved by its frictional contact with the check strap when the latter is moved in a reverse direction from that indicated by arrow *a*, Fig. 2, said movement being caused by the movement of the picker stick 12 in the operation of impelling the shuttle from the shuttle box. When the friction member 26 is located in this position a greater portion of the resistance that said friction member is provided to create upon the check strap is relieved.

The general operation of the structure hereinbefore specifically described is as follows: During the operation of the loom as the shuttle 28 is driven across the lay 10 and contacts with the buffer of the picker stick 12 upon entering the shuttle box, the picker stick driven toward the right as viewed in Fig. 2 will cause the loose portion of the check strap 14 located opposite the clamping member 16 therefor to be pulled across the curved faces 19 of the friction fingers 17 in the direction of the arrow *a*, Fig. 2. At the start of this movement of the check strap 14 the friction member 26 is located as indicated in Fig. 3 in contact with the stop 31 and the friction created upon the check strap is reduced to a considerable extent. When however the picker stick contacts with the right hand portion of the loop of the check strap as indicated in Fig. 2 the impetus given to the check strap to move the latter in the direction of the arrow *a* will cause the friction member 26 to move to the position illustrated in said Fig. 2 forcing the check strap rearwardly between the fingers 17 and thereby increasing the tension upon the check strap at a time when it is needed to bring the picker stick and shuttle to a stop. When, however, the picker stick is driven toward the left in Fig. 2 to discharge the shuttle 28 from the shuttle box, the picker stick upon contacting with the opposite side of the loop of the check strap causes said strap to be moved in an opposite direction from that indicated by the arrow *a* and the friction of the strap upon the friction member 26 will cause the latter to be moved from the position illustrated in Fig. 2 to that illustrated in Fig. 3, thereby greatly relieving the pressure upon said strap and reducing the friction thereon created by the friction fingers and by the friction member 26 at a time when friction is not necessary or desirable and in a manner to reduce the wear upon the check strap. The friction created and relieved by the use of the structure of this invention is varied as may be desired by adjusting the position of the bracket 23 toward or away from the check strap, and in the event that an arcuate surface 27 of the friction member 26 becomes worn to such an extent that its usefulness is impaired the position of said friction

member is reversed upon the bracket 23 to provide a new friction surface for engagement with the check strap. By constructing the friction member 26 of graphited Bakelite heat caused by friction is greatly reduced.

In Figs. 4 and 5 I have illustrated a modified embodiment of my invention in which a movable friction member 32 constructed of metal and having an arcuate surface 33 arranged to frictionally contact with a check strap 14 is rigidly fastened in any suitable manner to a pin 34 by which it is pivotally mounted in a bearing 35 forming a part of a bracket 36 which is adjustably secured to an arm 21 of a guide member 11 by means of a bolt 24 in exactly the same manner as is the bracket 23 previously described. The friction member 32 is normally held in the position illustrated in full lines in Fig. 4 against a stop 37 provided upon the bracket 36 by means of a helical spring 38 which surrounds the pin 34 below the bearing 35 and above the collar 39 which is rigidly fastened to said pin, opposite extremities of said spring interlocking with said bearing and collar in a manner to obtain the tension desired to check the movement of the picker stick and shuttle. A movement of the check strap toward the left in Fig. 4 will cause the friction member 32 to assume a position approximately as illustrated in light dash lines in said Fig. 4 causing the check strap to travel in a more direct path between the friction fingers 17 and thereby reducing the resistance to the movement of the check strap and reducing the wear thereon.

In Figs. 6 and 7 I have illustrated still another modified embodiment of my invention in which a movable friction member 40 formed as a roller is mounted upon a bracket 41 to rotate in one direction while in contact with a check strap 14 but is prevented from rotating in an opposite direction upon said bracket. The bracket 41 is adjustably secured to the arm 21 of the guide member 11 by means of a bolt 24. The roller 40 is positioned upon the bracket 41 between ears 42 and is rotatable upon a pin 43 in the direction of the arrow *b*, see Fig. 6. The movement of the roller 40 however in an opposite direction is prevented by a small cylindrical member 44 which is held in a space provided between the roller 40 and an edge 45 of the bracket 41 by means of a spring 46. When the check strap 14 is forced toward the right in Fig. 6 by the action of the picker stick 12 the roller 40 is prevented from rotating and a friction is created upon the check strap sufficient to check the movement of the picker stick and shuttle, but when the check strap is moved toward the left in said Fig. 6 the roller 40 is permitted to rotate thereby reducing the resistance to the movement of the check strap and consequently reducing the wear thereon.

The various embodiments of this invention hereinbefore described all function in a manner to produce a friction upon the check strap and retard the movement thereof when the shuttle enters the shuttle box and to reduce the friction upon said strap when the shuttle is discharged from said shuttle box. In each embodiment of the invention wear upon the check strap is reduced.

I claim:

1. In a loom the combination with a lay having a pair of rigid friction fingers embodied therein of a picker stick, a check strap for said picker stick immovably secured upon one side thereof to said lay and frictionally contacting

upon an opposite movable side thereof with both of said fingers, and a movable friction member positioned upon the lay to engage said check strap between the fingers and to be moved automatically by the check strap during free sliding movements of the latter in opposite directions across the fingers to automatically increase the friction upon the check strap in one direction and decrease said friction in the opposite direction.

2. In a loom the combination with a lay having a pair of friction fingers embodied therein of a picker stick, a check strap for said picker stick immovably secured upon one side thereof to said lay and frictionally contacting upon an opposite movable side thereof with both of said fingers, a friction member pivotally mounted upon the lay and positioned to co-operate with said fingers and to be contacted by the check strap during free sliding movements of the latter in opposite directions across the fingers to increase the friction upon the check strap in one direction and decrease said friction in the opposite direction, and means to restrict the rocking movement of the friction member to prevent a clamping engagement of the latter with the check strap.

3. In a loom the combination with a lay having a pair of friction fingers embodied therein of

- a picker stick, a check strap for said picker stick immovably secured upon one side thereof to said lay and frictionally contacting upon an opposite movable side thereof with both of said fingers, 5 a friction member pivotally mounted upon said lay and positioned to co-operate with said fingers and to be contacted by the check strap during free sliding movements of the latter in opposite directions across the fingers to increase the friction upon the check strap in one direction and decrease said friction in the opposite direction, means to hold said friction member in yielding contact with the check strap, and means to restrict the rocking movement of the friction member to prevent a clamping engagement of the latter with the check strap.
- 10 4. In a loom the combination with a lay having a pair of friction fingers embodied therein of a picker stick, a check strap for said picker stick immovably secured upon one side thereof to said lay and frictionally contacting upon an opposite movable side thereof with both of said fingers, 15 a roller mounted upon the lay and contacting between the fingers with the movable side of the check strap to be rotated thereby in one direction, and means to lock said roller against rotation when the check strap is moved in the opposite direction.
- 20 25
